UNITED STATES PATENT OFFICE.

WILLIAM F. BARRETT, OF ORANGEBURG, NEW YORK, ASSIGNOR TO
EMPIRE ENGINE AND MOTOR COMPANY, A CORPORATION OF
NEW YORK.

ROTARY ENGINE.

SPECIFICATION forming part of Letters Patent No. 741,574, dated October 13, 1903.

Application filed November 20, 1902. Serial No. 132,129. (No model.)

To all whom it may concern:

Be it known that I, WILLIAM F. BARRETT, of Orangeburg, in the county of Rockland, State of New York, have invented certain new and useful Improvements in Rotary Engines, of which the following is a complete specification, reference being had to the accompanying drawings.

My invention relates to improvements in rotary engines, particularly, but not exclusively, of the type adapted to be operated by compressed air, and has for its object the production of improved means for setting the piston-blades into operative position.

15 In the accompanying drawings, Figure I is a side elevation of a preferred form of embodiment of my engine. Fig. II is a central transverse vertical section thereof. Fig. III is a similar section taken at right angles to that shown in Fig. II. Fig. IV is a perspective view of the valve-stem detached; Fig. V, a similar view of the valve detached, and Fig. VI a similar view of one-half of the two-part piston-blade.

25 Referring to the numerals on the drawings, 1 indicates the outer cylindrical shell of a rotary engine of a well-known type. It is provided at opposite ends with flanges 2 and 3, against which, respectively, are secured heads 4 and 5, as by series of screw-bolts 6 and 7. The heads 4 and 5 are respectively provided with coaxial bearings 8 and 9, respectively, that are preferably made integral with their respective heads, and being preferably provided, respectively, with bushings 10 carry the trunnions 11 and 12 of the piston. The piston, as illustrated, is composed of disk-heads 15 and 16, secured to and preferably forming a part of the trunnions 11 and 12, respectively. The disk-heads 15 and 16 fit snugly but revolutely within the shell 1, with which the trunnions are concentric, and are united by an eccentric two-part piston the parts of which are indicated by the numerals 45 17 and 18. (See Fig. II.) The disk-heads are united to the two-part cylinder by screws, which are not illustrated, but for the reception of which screw-holes 19 are shown in Fig. II, and they indicate relative arrangement of 50 the screws. The parts 17 and 18 are provided with parallel transverse walls 20 and 21, which

define between them a transverse piston-blade recess and which are supported by brace-walls 22 and 23, respectively. It may be observed that the parts 17 and 18 constitute a complete cylinder only when they are properly assembled with their disk-heads 15 and 16.

25 and 26 indicate a two-part piston-blade working in the space or recess defined by the walls 20 and 21.

27 indicates a spring-projected block working in a recess provided in the thickened portion 28 of the shell 1, within which also ports 29 and 30 are located.

31 indicates the valve-head of the engine, that is provided with a plane upper surface 32, which constitutes the seat for the controlling-valve. The head 31 is provided with chambers 33, 34, and 35. The chambers 33 and 35, respectively, are provided with ports 36 and 37, (see Fig. II,) and the chamber 34 is provided with an inlet-port 38 and an exhaust-port 39. (Compare Figs. II and III.) The ports 29 and 30 lead from the chambers 33 and 35, respectively, to the interior of the shell 1, upon opposite sides of which they enter.

Rotary engines identical for the most part with the construction previously specified and provided with some form of controlling-valve and some means of setting the piston-blade different from the members herein shown and described for performing the functions required of those elements are well known in the art.

My invention, as has been hereinbefore set forth, relates to the means for controlling the supply and exhaust to the piston, including the controlling-valve, and to means for setting the piston-blade into operative positions. With respect to the former I provide in addition to the valve-head 31, with its connections, a valve-case 41, surmounting the valve-head and with it secured to the shell 1, as by screw-bolts 42, of which two are clearly shown in Fig. III of the drawings. The screw-bolts 42 pass through apertures provided for them in the valve-case and valve-head, respectively, and serve to rigidly assemble those parts 95 against the head 43, provided upon the shell 1. Within the valve-case 41 a valve 44, of rec-

tangular oblong cup shape, works upon the valve-seat 37, its dimensions being such as to cover at the same time the port 38, together with either but not both of the ports 36 and 37. 5 45 indicates the main supply-port of the engine, located, preferably, in the top of the valve-case 41. Incoming air or other fluid supplied through the port 45 serves to force the valve 44 firmly against its seat and finds 10 admission to the interior of the cylinder through either of the ports 36 and 37 which is open. As the means for actuating the said valve without tendency to disturb its relation to its seat and with positive provision to hold 15 it during its movements in fixed alinement I provide (see Fig. V) upon top of the valve two oblong lugs 47 and 48, which define a stem-retaining slit 49 between them. Into the slit 49 loosely fits the flattened portion 50 of the 20 valve-stem 51, defined by shoulders 52 and 53 therein. The valve-stem, passing through a stuffing-box 54 in the valve-case 41, terminates in an annular groove 55, adapted to operatively engage an actuating member—such, for 25 example, as the familiar lever provided with a bifurcated end. Illustration of such a lever is omitted, and the groove 55 is merely shown suggestively of means for imparting endwise movement to the valve-stem. In addition to the security against leakage afforded 30 and maintained in the construction of the valve shown and described there are also distinct advantages therein in the facility with which repairs and renewals of parts may be 35 effected.

With respect to the means for setting the two-part piston-blade into operative positions I provide in the inner edge of each part of the blade a recess 57. (Compare Figs. II, 40 III, and VI.) These recesses constitute pock- 45 ects for the driving fluid of the engine, which when admitted through the port 45 instantly drives them asunder and into operative contact with the inner face of the shell 1. My invention in this regard consists in the simplicity of construction of the piston-blade as a whole and in the means of admitting the driving fluid into the recesses 57, such means being afforded by making the space between 50 the walls 20 and 21 a hair's breadth wider than the actual accommodation of the piston-blade requires. Care should be exercised in deter-

mining the relative dimensions of the parts referred to, inasmuch as leakage is to be guarded against, and only so much force is 55 required to separate the parts of the piston-blade as shall insure their initial operation. When once the piston is in rotation, centrifugal force serves to hold the parts of the blade in working contact with the shell 1. It is in 60 consequence of this fact that the piston-blades may be used until they are worn nearly into their recesses 57, and for that reason and also by making the blades of comparatively heavy metal, which in my present construction is 65 in itself desirable, the life of the piston is considerably extended in practice. The piston-blade air-inlet aperture or crevice is indicated by the reference-numeral 58 in Figs. II and III. 70

In operation driving fluid is supplied through the port 45 into the interior of the valve-case 41, whence, the valve being in position shown in Fig. II, it passes through the port 37, chamber 35, and port 30 into the interior of the shell 1, where it expands against the part of the piston-blade presented in front of it, the two parts of the said piston-blade being actuated in the manner already described by passage of a part of the fluid 80 through the crevice 58 into the opposing recesses 57. The rotation of the piston drives the exhaust through the port 29, chamber 33, port 36, the valve 44, and chamber 34 to the exhaust-outlet 39. If the position of the 85 valve 44 be shifted, the inlet and outlet courses are reversed, the chamber 34 being the common discharge-outlet to the one or the other of the chambers 33 and 35. 90

What I claim is—

The combination with a rotary engine, including its shell and piston, of a two-part piston-blade, provided with opposite interior recesses, working between walls provided for it in the piston, the distance between said walls being slightly in excess of the thickness of the blade, substantially as and for the purpose specified. 95

In testimony of all which I have hereunto subscribed my name.

WILLIAM F. BARRETT.
